UNITED STATES PATENT OFFICE.

SIMON DICK, OF PARIS, FRANCE.

MECHANICAL HAND FAN.

Application filed October 31, 1913: Serial No. 798,444.

To all whom it may concern:

Be it known that I, SIMON DICK, a citizen of the Republic of France, residing at 17 Passage des Panoramas, Paris, in the 5 Republic of France, have invented certain new and useful Improvements in Mechanical Hand Fans, of which the following is a specification.

This invention relates to a fan for personal use adapted to be collapsed or folded for carrying in the pocket and to be operated by hand. It has for its object the provision of a rotary fan of very compact construction such that it can be carried in a 10 pocket case, which can readily be started with very little effort, and in which the blades can be folded one upon the other when not in use or even detached completely from the mechanism, in such a manner as 15 to reduce the bulk of the device to the minimum.

The invention will be described with reference to the accompanying drawing, and afterwards pointed out in the claims.

25 In the said drawings:—

Figure 1 is a front elevation of the operating mechanism for the blades which are shown superposed in the inoperative condition.

30 Figure 2 is a corresponding plan partly in section.

Figure 3 is a rear elevation similar to that in Figure 1.

35 Figures 4 and 5 are detail views to a larger scale showing the mounting of the blades.

Referring to the accompanying drawings a vane or blade wheel preferably comprising 40 three blades k , k' , k'' are mounted on a shaft j . This shaft j , which is supported in front by a bracket h , carries a rigidly mounted pinion i meshing with a gear wheel f of larger diameter loosely mounted upon a shaft g . Upon the shaft g is a pinion e and a rigidly connected ratchet wheel m . A pawl n acted upon by a spring o is fixed 45 upon the wheel f in such a manner that the pinion e drives the wheel f in one direction only. This pinion e is driven by a rack c formed upon or rigidly connected with a movable frame a terminating with a knob b . The movable frame is guided between a plate p supporting the mechanism and a fixed front plate d .

50 55 By holding the device between the thumb and the index finger, it is possible to exert

pressure with the thumb against the knob b and displace the rack c longitudinally and consequently rotate the pinion e . This displacement drives the wheel f and, accordingly the blade wheel k , k' , k'' by the intermediary of the pinion i and of the shaft j . The frame a is displaced in the opposite direction by a spring l which returns it to its initial position when the pressure of the thumb ceases; this spring is fixed at one of its ends a' to the movable frame a and at the other extremity d' to the fixed plate, d .

Owing to the inertia of the blade wheel, it is possible by imparting a reciprocating movement to the frame a to obtain a continuous movement of rotation of the blade wheel and consequently a continuous current of air.

In order to render the device readily transportable and to constitute a mechanical fan which can readily be carried in the pocket, the blades are constructed in such a manner that they can be folded one upon the other. With this object in view they are each provided with a hub portion having a circular orifice and are mounted on a short hollow shaft or sleeve r being held in place on said shaft or sleeve r by two washers g and s which are rendered integral with the shaft r by means of a set screw t . The hollow shaft or sleeve r is adapted to be passed onto the end of the shaft j and fits sufficiently tightly thereon to revolve therewith and does not require any securing means so that it may readily be removed therefrom.

One of the fan blades may be fixed on the shaft r while the remaining blades are mounted loosely thereon so that they may be rotated to be superposed upon the fixed blade for convenience in carrying. Each of the blades has upon its hub portion a lug or projection v which when the blades are spread apart contacts with a lug or projection u integral with one of the said washers so that the blades rotate with the shaft j . It will be understood that the blades are held permanently on said shaft or sleeve r by the washers and are removed from the shaft j with the shaft r in one simple movement.

In order to make the device small enough to place the device in the pocket, the blades k , k' , k'' are folded back one upon the other by rotation about the shaft r and this shaft is disengaged from the shaft j . This ro-

tation is effected in the same direction as that of the shaft *j* in such a manner that when the said shaft *j* is subsequently rotated the blades open out automatically under the influence of inertia.

It should be noted that without departing from the principle of the invention, numerous modifications can be introduced into the device. For example the blade 10 wheel might be replaced by a dismountable propeller screw with an appropriate number of blades and the case might be provided with a special pocket for the reception of the detachable set of blades and so forth.

15 From the foregoing explanation it follows that the mechanism is very compact and can therefore readily be placed in a small pocket case from which only the pusher *b* protrudes.

20 What I claim and desire to secure by Letters Patent of the United States is:—

1. In a fan, the combination of a fan shaft, a pinion thereon, a reciprocating plunger, a rack on said plunger, a spring 25 applied to said plunger for maintaining the same normally extended, gearing in train with the rack on said plunger and the pinion on said fan shaft, a casing which encloses said gearing provided with holes 30 through which said plunger and fan shaft project, a fan secured to rotate with said fan shaft, the blades of which are pivotally movable relatively to each other to provide for folding and extending said fan 35 blades, means for maintaining said fan blades yieldingly in folded and extended positions.

2. In a pocket fan, the combination of a casing, a fan shaft mounted therein and extending through the front wall thereof, fan blades mounted on the projecting end of said shaft, a pinion on said shaft within the casing, an operating plunger extending through one end of the casing and reciprocable toward and from the fan shaft, means in the casing for normally maintaining the plunger yieldingly extended, a rack carried by the inner end of said plunger, and gearing in train with the rack and the pinion 45 on the fan shaft for imparting continuous rotary motion to the fan shaft upon reciprocation of the plunger, whereby said fan is adapted to be supported and operated by a thumb and finger of one hand.

50 3. In a pocket fan, the combination of a casing, a fan shaft extending through the front wall thereof, fan blades mounted on said shaft and capable of relative pivotal movement thereon to provide for nesting the blades when not in use, an operating plunger extending through one end of the casing and reciprocable toward and from the opposite end of the casing, and means in the casing for normally pressing the 55 plunger outwardly and for imparting a con-

tinuous rotary motion to the fan shaft upon reciprocation of the plunger.

4. In a pocket fan, the combination of a casing, a fan shaft extending through the front wall near one end of the casing, fan 70 blades mounted on said shaft capable of relative pivotal movement thereon to provide for nesting the blades when not in use, an operating plunger extending through the end of the casing opposite that at which the fan shaft is mounted, said plunger being located close to the rear wall of the casing and reciprocable toward and from the fan shaft, and means in the casing for normally pressing the plunger outwardly and for imparting a continuous rotary motion to the fan shaft when the plunger is reciprocated, the nested blades being substantially the same length as the casing and plunger, and the casing and plunger being of such size 85 as to be adapted to be held and operated by a thumb and finger of one hand.

5. In a pocket fan, the combination of a casing, a fan shaft mounted therein, and extending through the front wall thereof, fan blades mounted on the projecting end of said shaft, a pinion on said shaft, a plunger mounted symmetrically astride upon the fan shaft and reciprocable thereon, a rack carried by said runner, and gearing in train 90 with the pinion on said fan shaft, for imparting a continuous rotary motion to the fan shaft upon reciprocation of the plunger, whereby the unitary whole is adapted to be held between the forefinger and thumb of 100 one hand and operated thereby.

6. In a pocket fan, the combination of a relatively small casing, a fan shaft mounted therein and extending through the front wall thereof, fan blades mounted on the projecting end of said shaft, a pinion on said shaft, a plunger mounted symmetrically astride upon the axis of said shaft, a controlling rack carried by said plunger, adapted to gear in train with the pinion on the fan shaft 105 for imparting continuous rotary motion to said fan shaft upon reciprocation of said runner, whereby the fan can be operated by the thumb and forefinger of one hand.

7. In a pocket fan, the combination of a casing, a fan shaft centrally mounted therein and extending through the front wall thereof, fan blades mounted on the projecting end of said shaft, a plunger mounted symmetrically astride upon the fan shaft 110 and reciprocable thereon, a rack carried by said plunger, and gearing in train with the pinion on said fan shaft, for imparting a continuous rotary motion to the fan shaft upon reciprocation of the plunger, whereby the unitary whole is adapted to be held between the forefinger and thumb of one hand 120 and operated thereby.

8. In a pocket fan, the combination of a small casing, a fan shaft mounted centrally 125

therein and extending through the front wall thereof, fan blades mounted upon the projecting end of said shaft, a pinion on said shaft, a plunger mounted symmetrically astride upon the axis of said shaft, a controlling rack carried by said plunger, 5 adapted to gear in train with the pinion on the fan shaft for imparting continuous rotary motion to said fan shaft upon reciprocation of said plunger, whereby the fan can be operated by the thumb and forefinger of one hand.

9. In a pocket fan, the combination of a small circular casing, a fan shaft centrally mounted therein and extending through the front wall thereof, fan blades mounted on

the projecting end of said shaft, a pinion on said shaft, a plunger mounted symmetrically astride upon the axis of said shaft, a controlling rack carried by said plunger, 20 adapted to gear in train with the pinion on the fan shaft for imparting continuous rotary motion to said fan shaft upon reciprocation of said plunger, whereby the fan can be operated by the thumb and forefinger 25 of one hand.

In testimony whereof I affix my signature in presence of two witnesses.

SIMON DICK.
